UNITED STATES PATENT OFFICE.

JOHN TAYLOR HAYNE, OF BUFFALO, NEW YORK.

SUPPLEMENTAL RUNNING-BOARD FOR AUTOMOBILES.

1,294,904.

Specification of Letters Patent.

Patented Feb. 18, 1919.

Application filed March 17, 1917, Serial No. 155,542. Renewed December 11, 1918. Serial No. 266,363.

To all whom it may concern:

Be it known that I, JOHN TAYLOR HAYNE, a citizen of the United States, residing at Buffalo, in the county of Erie and State of New York, have invented certain new and useful Improvements in Supplemental Running-Boards for Automobiles, of which the following is a specification.

This invention relates to automobile running-board attachments, and pertains especially to a supplemental running-board for the usual or ordinary running-boards of automobiles.

The object of the invention is to provide an improved article of manufacture constituting a complete supplemental running-board adapted to be slipped endwise on and off the usual or ordinary running-boards of automobiles, especially of the Ford type.

A further object of the invention is to provide a supplemental slip-on running-board for the ordinary running-boards of automobiles, which shall be of such construction as to form a complete cover for and preserve the ordinary boards against rusting and the usual wear and disfigurement thereof.

A still further object of the invention is to provide a protection for ordinary running-boards which shall constitute a supplemental running-board complete in itself and having such construction as to be slid on and off the ordinary boards endwise, and as to be held on the ordinary boards without bolts, rivets, screws or any such fastenings for connecting the supplemental board with the ordinary boards.

A still further object of the invention is to provide in a supplemental running-board such construction and arrangement of parts as to cushion the supplemental boards on the ordinary boards and thereby prevent rattling of and friction between the boards, and also to preserve the ordinary boards from the effects of water and the usual wear elements which impair and disfigure the ordinary boards.

Various other objects, advantages and improved results will be found in the manufacture and practical application of the invention as will be hereinafter disclosed.

In the accompanying drawings forming part of this application:—

Figure 1 is a perspective view of a run-

ning-board in position on a Ford type of automobile with my supplemental board applied thereto.

Fig. 2 is a perspective view of part of an ordinary detached running-board showing my supplemental board partly in section as being slid onto the ordinary board.

Fig. 3 is a section on the dotted line A—A Fig. 2.

Fig. 4 is an inverted perspective view of part of a supplemental board.

Fig. 5 is a perspective view of a modification partly broken away showing a board ready to be applied to an ordinary board.

Fig. 6 is a perspective view showing the board in Fig. 5 as applied to an ordinary board.

Fig. 7 is a perspective view of a further modification.

Fig. 8 is a section taken on the dotted line B—B, Fig. 6.

The same reference characters denote the same parts throughout the several views of the drawings.

In carrying out my invention, I employ a principal or main plate 1, preferably of sheet metal and of such weight as desired to afford sufficient thickness so as not to be deflected, bent or punctured when applied to an ordinary running-board 2, having surface protrusions 3, as of the Ford type automobiles, or any other type employing similar removable boards. To the upper or outer face of the plate 1, is applied a plate 4, preferably of linoleum or other similar or suitable composition or fabric material having its outer surface cross-hatched in squares or other designs to form an anti-slip ornamental tread surface, and said surface may be of any desired color. The tread plate 4 is preferably gummed or glued to the plate 1 with the edges of these plates flush. The under or inner face of the plate 1 is provided with a textile baize, cloth, felt or other similar lining 5, the edges thereof being preferably flush with the edges of the plates 1 and 4.

The means embodied in the supplemental board for connecting it with the ordinary boards, comprises a pair of side binding rims 6, having a pliable or flexible member 7, lined with material 8 like or similar to the lining 5, or in the same piece therewith, preparatory to applying the rims to the

plates 1 and 4, and in further preparation of the rims for said application, they are bent at 9 and 10, and have mitered ends 11, corresponding with the ends of a pair of end binders 12 for the ends of the plates 1 and 4. The means for attaching the binders to the plates will now be described. Longitudinal cleats 13 and cross cleats 14, preferably of hard wood or other suitable material, are placed on the under or inner side of the plate 1 adjacent to the side and end edges respectively of said plate, and suitable screws 15 are passed through the rim 6 and binders 12, and through the plates 1 and 4, and into the cleats 13 and 14, thereby fixing all of said parts firmly and rigidly together, so that the rim member 7 is off-set from the plate edges, and depends from the top of the plate 4, and forms a groove for the side flanges 16 of the ordinary running-boards.

The cleats have functions other than forming anchors for the screws 15, as will now be explained. It is well known that ordinary running-boards, especially the Ford type, have a flat marginal surface at the sides and ends, and that the protrusions or other deflections such as 3 are within said margin and stand above said marginal surfaces which are usually used for attaching the ordinary boards in proper position on the usual brackets by means of suitable bolts. I utilize part of this marginal surface as a seat for the cleats 13, which are of such thickness as to more than equal the height of the usual protrusions or deflections in ordinary running-boards. The cleats prevent pressure of the plate 1 of the supplemental board on the protrusions, so that the cleats and the lining 5 protect and preserve the polished surfaces of the ordinary boards to the avoidance of friction and rattling, and also cushion the boards. A further function of the cleats is that they exclude water and other objectionable elements from the ordinary running-boards, and the cleats also form guides or runners in sliding the supplemental boards on and off the ordinary boards, as more clearly shown in Fig. 2 of the drawings.

Obviously in applying the supplemental boards the ordinary boards are removed from an automobile and the supplemental boards are slid endwise on to the ordinary boards where the former are held in place to fully cover the latter by means of the side rims hugging the side flanges of the ordinary boards. After the boards are connected, the flexible members of the said rims may be further bent to more closely impinge said flanges as desired or as occasion may demand. Then the two boards connected together as above described are placed on the automobile brackets and the ordinary boards are secured as usual to said brackets.

It will be seen that the supplemental

boards are free to be given sliding movement whenever the ordinary boards are removed from an automobile, that the supplemental boards are complete articles and embody as part thereof the only means for slidably connecting the supplemental boards with the ordinary boards, that the supplemental boards or any part thereof may be changed or removed by merely sliding these boards off the ordinary boards, and that the placing and removal of the supplemental boards intact with respect to the ordinary boards is accomplished merely by sliding the respective boards endwise.

Referring to the modification shown in Figs. 5, 6 and 7, the tread plate 17 and its supporting plate 18, and the rims or binders 19 and 20, are riveted together as at 21, and the felt or other lining 22 is glued or gummed to the plate 18 over the inner ends of the rivets which are flush with this plate. The ends of this board are provided with a bendable flange 23 which may be extensions of the binders 20, or they may be riveted to or extensions of the plate 18 as 23a. After this supplemental board is telescoped onto the ordinary board 24, and in order to effectually close the end openings between the boards and to afford additional connection, the flanges 23 are bent around the ends of the ordinary boards 24 and impinge the under face thereof. The lining 22 is made to extend over the inner face of the flanges 23, so that the said lining is the only part of the supplemental board coming in contact with the ordinary board. The cleats are not used in this form of board.

Obviously the simplicity of construction affords a light weight, ornamental supplemental board capable of being expeditiously slid in its entirety on and off an ordinary board without the use of bolts, screws and the like, and without the usual expenditure of time in operating the same, and in adjusting any parts for attaching the supplemental boards.

It will be understood that preparatory to constructing the supplemental boards, the parts thereof are all shaped and formed ready for assembling in one complete article of manufacture, and these boards are manufactured in a complete article ready to be applied.

I do not wish to be understood as confining my invention to any particular size, shape or material therein or in the parts thereof, nor do I wish to limit myself in the application of the invention, but reserve the right to make such changes and variations in the complete article and in the parts thereof, and to vary the same in the practical manufacture and application thereof, as may come within the scope of the appended claims.

Having thus described my invention what

I claim as new and desire to secure by Letters Patent is:—

1. A supplemental slide-on running-board for the ordinary running boards of automobiles, comprising an inner plate, an outer tread-plate mounted on the inner plate, binding rims for said plates, certain of said plates constituting the only retaining means between the supplemental and ordinary boards, and means for securing said plates and the rims together.

2. A supplemental slide-on running-board for the ordinary running-boards of automobiles, comprising an inner plate, an outer

tread-plate of different material mounted on 15 the inner plate, a lining on the inner face of the inner plate of different material from that of the said plates, and rims upon one of the plates for binding the plates together and constituting the only connection between 20 the respective boards.

In witness whereof I hereunto set my hand in the presence of two witnesses.

JOHN TAYLOR HAYNE.
